UNITED STATES PATENT OFFICE

165,613

CLOCK CASING OR SIMILAR ARTICLE

John W. Smith, Killbuck, Ohio

Application June 6, 1949, Serial No. 3,069

Term of patent 7 years

(Cl. D42—7)

To all whom it may concern:

Be it known that I, John W. Smith, a citizen of the United States, residing at Killbuck, in the county of Holmes and State of Ohio, have invented a new, original, and ornamental Design for a Clock Casing or Similar Article, of which the following is a specification, reference being had to the accompanying drawing, forming part thereof.

Figure 1 is a front elevational view of a clock casing or similar article, showing my new design, and

Figure 2 is a top perspective view thereof.

I claim:

The ornamental design for a clock casing or similar article, as shown.

JOHN W. SMITH.
